UNITED STATES PATENT OFFICE

112,014

DESIGN FOR A SHOE OR SIMILAR ARTICLE

Paul J. C. Wolfer, Wellesley, Mass.

Application September 3, 1938, Serial No. 79,746

Term of patent 7 years

To all whom it may concern:

Be it known that I, Paul J. C. Wolfer, a citizen of the United States and a resident of Wellesley, county of Middlesex, and State of Massachusetts, have invented a new, original, and ornamental Design for a Shoe or Similar Article, of which the following is a specification, reference being had to the accompanying drawing, forming part thereof.

In the drawing:

Fig. 1 is a plan view of a shoe showing my new design, and

Fig. 2 is a side elevational view of the same.

I claim:

The ornamental design for a shoe or similar article, substantially as shown.

PAUL J. C. WOLFER.
